UNITED STATES PATENT OFFICE.

EDWARD M. FRITZ, OF GRAND RAPIDS, MICHIGAN, ASSIGNOR TO GRAND RAPIDS CABINET COMPANY, OF GRAND RAPIDS, MICHIGAN, A CORPORATION OF MICHIGAN.

BRICK ICE-CREAM PACKING AND COOLING CABINET.

Application filed July 25, 1927. Serial No. 208,222.

This invention relates to ice cream cabinets, and is particularly concerned with a structure of cabinet for the packing and cooling or refrigerating of brick ice cream.

- 5 It is the object and purpose of the present invention to provide a novel form of cabinet and particularly a novel form of holder or container for brick ice cream which may be placed in the cabinet, one or more of the 10 same, whereby the bricks of ice cream may be maintained at a desired low temperature, the refrigerant holding receptacles at all times being free of the brick ice cream holding receptacles, not freezing together, and 15 whereby a proper circulation of air within the cabinet is provided, thereby making the temperature substantially uniform within said cabinet.

An understanding of the invention may 20 be had from the following description taken in connection with the accompanying drawing, in which,

Fig. 1 is a vertical transverse section through the cabinet of my invention.

25 Fig. 2 is a plan view thereof, the upper closures of the cabinet being removed, and

Fig. 3 is an enlarged perspective view of one of the brick ice cream holding containers.

30 Like reference characters refer to like parts in the different figures of the drawings.

The cabinet 1 is of well known construction, having a bottom, vertical sides and ends, and an open top in which there is a 35 large opening to receive the ice cream holding cans and the refrigerant holding receptacles. Said recess is properly lined and is insulated from the outside by means of cork board or other suitable insulation. The cabinet is of the type and construction shown in the patent to Phillip Fritz, issued 40 January 5, 1926, No. 1,568,216, and its specific structure need not be further set forth.

45 In cabinets of this type there is a central well 2 extending lengthwise of the cabinet, above which the opening in the cabinet is widened, with the provisions of shelves 3, one at each side and a distance above the 50 lower end of the well 2, on which receptacles 4 containing the refrigerant, ice and salt, are located. A plurality of such receptacles are placed at each side of the well with their

inner sides in vertical planes, and their outer sides tapering upwardly and outwardly from the vertical. Such receptacles, by reason of the limited height thereof and because in the length of the cabinet a number of the same are used, are light enough, even when filled with crushed ice and salt, 60 and are of such height that they are readily and easily handled for placing in or taking out of the cabinet.

It is between the refrigerant holding receptacles 4 that the ice cream containers are 65 placed. With my invention the ice cream containers each consist of a sheet metal can, substantially square in outline, having an upper end and of such size that the lower end of the can may be received in the well 70 2 to lie between the refrigerant holding receptacles 4 at opposite sides of the cabinet.

With my invention each side of the can 5 is formed with a plurality of outwardly pressed embossings or projections 6. In 75 practice there are a pair of said projections near both the upper and lower ends of each side of the can. All of the projections 6 at the lower end of the can lie in the same horizontal plane. Likewise all those at the 80 upper end of the can lie in the same horizontal plane.

When these cans are placed in the cabinet the lower projections 6 are in the well 2 and may bear against the vertical sides of the 85 lining of the well, thus locating the can in the well and holding spaced apart the sides of the can and the sides of the well. The cans 5 which are at the ends of the well are likewise spaced from the end of the linings 90 of the cabinet by the projections 6. The adjacent sides of two cans 5 are spaced apart by reason of the fact that the projections 6 made on the adjacent sides of the two cans come directly against each other as fully 95 shown in Fig. 2. It is also evident that the inner sides of the ice cream holding receptacles 4 are held spaced from the sides of the cans 5 by the upper projections 6. This insures that entirely around each one of the brick holding cans 5 there is a continuous air space, permitting free downward movement of cold air from the inner sides of the refrigerant holding receptacles between the cans and upwardly between said 100 cans and between the end cans and the ends 105

of the cabinet. The sides of the cans 5 are provided with a large number of perforations for further aiding the circulation and bringing the cold air in contact with the ice cream held in said cans.

The space between the ice cream holding cans 5 and the refrigerant holding receptacles 4 also precludes any possibility of intimate contact between the sides of the said cans and receptacles and their freezing together as would otherwise occur. Such freezing together is very undesirable, restricts circulation, defeats uniformity of temperature and makes it hard to remove the refrigerant holding receptacles when the same are to be drained and replenished with refrigerant.

It is, of course, evident that it is not necessary to use the brick ice cream holding cans 5 the entire length of the well, but that it is very easy to replace one or more of the cans 5 with regular cylindrical bulk holding ice cream cans, such bulk holding cans being interchangeable with the square cans shown in the present invention. It is further evident that the cans shown are not restricted in use to holding brick ice cream alone but that many other articles which are to be maintained in a cool condition, such as the so-called "Frost Bites", "Eskimo Pie" and the like and many and various articles of food may be held in such cans and maintained in proper refrigerated condition.

The invention is defined in the appended claims and should be considered comprehensive of all forms of structures coming within their scope.

I claim:

1. In an ice cream cabinet having an opening into which refrigerant holding receptacles are adapted to be placed, one at each side of the opening in spaced apart relation, a can of rectangular outline adapted to be located between the refrigerant holding receptacles and formed at its sides with outwardly pressed projections to engage against the adjacent sides of the refrigerant holding receptacles to thereby properly locate said receptacles and can with respect to each other and space the same from each other, said projections being spaced apart to per-

mit vertical air circulation past and between them.

2. A can adapted to be placed in ice cream cabinets, of rectangular outline having sides located substantially at right angles to each other, and projections pressed outwardly in opposite sides of said can and spaced apart to permit vertical air circulation past and between them, substantially as and for the purposes described.

3. A can of sheet metal open at its upper end adapted to be placed in an ice cream cabinet, having vertical sides located at right angles to each other, said can being of square outline, and projections pressed outwardly in each side of said can and spaced apart to permit vertical air circulation past and between them, the outer points of all the projections in a side of the can lying in substantially the same vertical plane.

4. In combination with an ice cream cabinet having an opening in its upper side, the central portion of which is deeper than at the side portions thereof, thereby forming a well, of a can of rectangular outline made of sheet metal located in said well the opposite sides of said can adjacent the sides of the well being formed with outwardly extending projections spaced apart to permit vertical air circulation past and between them, and refrigerant holding receptacles located at each side of the well with their inner sides contacting with the outer points of said projections on the can, said projections on the can located in the well contacting with opposite sides of the well.

5. A can for use with ice cream cabinets, made of sheet metal and square in cross section having vertical sides, a plurality of spaced apart projections extending outwardly from each side of the can adjacent the upper end thereof, said projections being pressed from the metal of the can and all located in the same horizontal plane, and other spaced apart projections pressed outwardly from each side of the can near the lower end thereof, all of said projections adjacent the lower end of the can lying in the same horizontal plane.

In testimony whereof I affix my signature.
EDWARD M. FRITZ.
